[57] CLAIM

The ornamental design for a combined binder and easel for storage and use of computer software and instructional material, as shown and described.

DESCRIPTION

FIG. 1 is a perspective view of a combined binder and easel for storage and use of computer software and instructional material, showing my new design;

FIG. 2 is a bottom rear perspective view thereof;

FIG. 3 is a perspective view thereof in the open position and in its easel configuration; and

FIG. 4 is a bottom rear perspective view thereof.
